C. C. HANSEN

REGULATING VALVE FOR ROTATION MOTORS

Filed Nov. 12, 1921

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

REGULATING VALVE FOR ROTATION MOTORS.

Application filed November 12, 1921. Serial No. 514,816.

To all whom it may concern:

Be it known that I, CHARLES C. HANSEN, a citizen of the United States, a resident of Easton, county of Northampton, and State 5 of Pennsylvania, have invented a certain Regulating Valve for Rotation Motors, of which the following is a specification accompanied by drawings.

This invention relates to fluid actuated 10 rock drills of the hammer type, but more particularly to a valve for automatically regulating the supply of fluid to the rotation motor of such a machine.

In United States Patents, Nos. 1,372,914 15 and 1,372,915, granted March 29, 1921, to W. A. Smith, assignor to Ingersoll-Rand Company, a valve for regulating the rotation motor is disclosed, so constructed however that the normal supply of fluid to the 20 motor cannot conveniently be controlled without the addition of a needle valve or other suitable device in the supply line, capable of ready and quick adjustment, although the said independent valve is not 25 shown in said patents.

The objects of the present invention are to improve upon a valve of the general type disclosed in said patents, and produce a unitary valve structure in which ready and 30 convenient manual rotary adjustments of the valve casing may be effected as desired for controlling the normal flow of fluid to the rotation motor without the provision of a separate valve in the supply line for this 35 purpose.

My improvement is illustrated in one of its preferred forms in the accompanying drawings, in which

Figure 1 is a side view partly in longitudinal section of a rock drill embodying my invention,

Figure 2 is a detail end view,

Figure 3 is a detail transverse sectional view on the line 3-3 of Figure 1, looking 45 in the direction of the arrows.

Figure 4, is a view similar to Figure 3 with the parts in a different position,

Figure 5, is a detail longitudinal sectional view through the valve structure showing 50 the valve in a different position, and

Figure 6, is a detail transverse sectional view on the line 6-6 of Figure 1 through the rotation motor looking in the direction of the arrows.

55 Referring to the drawings, only so much

of the operative parts of a fluid actuated rock drill of the hammer type is shown, as will serve to illustrate my invention. The machine comprises the cylinder A, having the front head B provided with the rotation 60 sleeve C through which the drill steel D extends in position to receive the impact of the reciprocating piston hammer E. A fluid actuated rotation motor of the gear type, having the gears F, is mounted in the back 65 end portion G of the cylinder, and the back head H is provided with a valve chest J for the automatic rotation motor regulating valve. The parts of the machine are secured together by the usual through bolts K. One 70 of the gears F is provided with a spindle F' having a pinion G' within the front head B, meshing with a gear H' on the rotation sleeve C, for imparting rotation to the drill steel D.

Motive fluid is supplied to the machine through the inlet L and passing from the usual throttle valve O, enters the valve chest J through the passage P. From the valve chest, the motive fluid passes through the 80 port Q and passage R to the rotation motor, exhausting from the motor through the exhaust ports S, into the exhaust passage T and thence to atmosphere.

The valve structure in the valve chest J 85 comprises a valve casing U, having a longitudinal peripheral groove V, forming an external passage partly within the enlarged bore W of the valve chest J and adapted to cooperate with the port Q leading to the 90 rotation motor. The valve casing U is also provided with a central passage X in its body portion, and radial passages Y in its sides, which are controlled by an automatic valve Z in the form of a plunger normally 95 maintained in closed position by a spring a adapted to be compressed between the valve and the end of a screw threaded adjusting screw b for adjusting the tension of the spring. The valve casing U is rotatable 100 within the valve chest J and may be manually adjusted to different rotary positions by means of the handle c, held upon the valve casing by means of the nut d and also provided with a spring pressed detent e, co-operating with the notches or depressions f on the face of the plate g adapted to be secured to the back head as by means of the screws h. The valve casing U has a swivel 105 connection with the valve chest J, so that the 110

5 casing can be rotated without being moved longitudinally in the valve chest. This connection between the valve casing and chest prevents the vibration of the drill from 10 moving the casing to admit a greater supply of motive fluid to the motor at periods when a stronger or faster rotation would be unnecessary.

10 In the operation of the device, the normal supply of fluid to the rotation motor is controlled by the rotary adjustment of the valve casing J which may be turned to the position indicated in Figure 3, in which the outside groove V of the valve casing registers completely with the port Q leading to the rotation motor or else intermediate positions may be selected, one of which is shown in 15 Figure 4, in which a less supply of fluid is passed to the rotation motor. When the motor slows down, under increased load, and the back pressure is sufficient to overcome the spring a, the automatic valve Z will open additional ports in the side and end of the valve casing, as indicated in Figure 20 5, to permit more fluid to pass to the rotation motor, as required.

I claim:

1. In a fluid actuated rock drill of the hammer type, the combination of a rotation 30 motor and a valve for automatically regulating the supply of fluid to said motor, said valve comprising a unitary casing rotatable in a supply conduit leading to the motor and itself controlling the normal supply of fluid to the motor, an automatic regulating valve within the said casing adapted to control additional air to the motor as required, and manual means for rotatably adjusting the casing in the said conduit to control the 35 flow of motive fluid to the motor without moving said casing longitudinally, including means for automatically locking the valve casing in different adjusted rotative positions.

40 2. In a fluid actuated rock drill of the hammer type, the combination of a rotation motor and a valve for automatically regulating the supply of fluid to said motor comprising a unitary casing rotatable in a supply 45 conduit leading to the motor and itself controlling the normal supply of fluid to the motor, a normally closed spring pressed regulating valve within the said rotatable casing adapted to control the amount of

50 fluid passing from the said conduit through ports in the side and end of the casing to the motor, and manual means for rotatably adjusting the casing in the said conduit to control the flow of motive fluid to the motor without moving said casing longitudinally, 55 including means for automatically locking the valve casing in different adjusted rotative positions.

3. In a fluid actuated rock drill of the hammer type the combination of a rotation 60 motor and a valve for automatically regulating the supply of fluid to said motor, said valve compressing a unitary casing rotatable in a supply conduit leading to the motor and itself controlling ports and passages 65 leading from the conduit to the motor, a normally closed spring pressed regulating valve within said rotatable casing adapted to control the amount of fluid passing from said conduit through ports in the sides and 70 end of the casing to the motor, and manual means for rotatably adjusting the casing in the said conduit to control the flow of motive fluid around the outside of the casing to the motor without moving said casing 75 longitudinally, including means for automatically locking the valve casing in different adjusted rotative positions.

4. In a fluid actuated rock drill of the hammer type, the combination of a rotation 80 motor, a valve chest having an end port eccentric to the axis of the chest and a valve in said chest for automatically regulating the supply of fluid to said motor, said valve comprising a casing rotatable in a supply 85 conduit leading to the motor, provided with a longitudinally extending groove and radial passages, and itself controlling the normal supply of fluid to the motor through said groove and passage, said casing also 90 having a centrally located longitudinal passage, an automatic regulating valve within said casing adapted to control additional air through said central passage to the motor as required, and manual means for rotatably 95 adjusting the casing in the said conduit, whereby said groove in the casing cooperates with the port leading to the motor for controlling the flow of motive fluid to the motor.

In testimony whereof I have signed this 100 specification.

CHARLES C. HANSEN.
